(57) **CLAIM**

The ornamental design for a gaming table with bet sensor as shown and described.

DESCRIPTION

FIG. 1 is a top perspective view of a gaming table with bet sensor showing our new design;

FIG. 2 is an enlarged view thereof corresponding to region 2 depicted in FIG. 1;

FIG. 3 is a top view thereof; and,

FIG. 4 is a cross-sectional view thereof taken through line 4-4 of FIG. 3.

The uneven-length broken lines immediately adjacent the shaded area in FIGS. 1-3 represent a peripheral boundary of the design and forms no part thereof. The even-length broken lines in FIG. 4 represent a sectional region of the gaming table that forms no part of the claimed design. The even-length broken lines depicting portions of the bet sensor and the remainder of the gaming table form no part of the claimed design.
